UNITED STATES PATENT OFFICE.

HAWKINS E. ROBESON, OF GARNER, TEXAS.

RAILWAY MOTOR CAR.

Application filed January 18, 1926. Serial No. 82,103.

This invention relates to certain new and useful improvements in railway motor cars, and particularly to motor cars of that type known as section cars.

5 Cars of this character should be strong in construction, in order to stand the strains to which they are subjected in use, but they are also required to be light in weight, in order that they may be conveniently handled, because the exigencies of the service frequently requires them to be lifted bodily off and onto the track. A difficulty with section cars of ordinary construction is that, because of their lightness of weight, the frames 15 thereof are liable to tack or twist laterally under running strains, with the result that the car is subjected to excessive vibration, the axles are often shifted out of alignment, and on rough or uneven tracks the flanges of the 20 wheels are liable to jump the rails and cause injuries to the car and passengers. It is frequently necessary for such cars to be taken off the track at places where there is no rest or set-off, in order to clear the way for 25 traveling trains, and this is often a time-consuming and laborious operation and frequently it is impossible for the crew to remove the car in time to prevent it from being struck by a passing train, thereby causing serious accidents. With section cars 30 of ordinary construction, breaking of axles, bearings or flanges of wheels is often caused by the same striking against the rails in the operation of applying the car to or removing it from the track.

35 One object of my invention is to provide means for bracing the frames of side cars, whereby greater rigidity is ensured to prevent excessive vibration, also to prevent 40 undue lateral swaying tending to cause the car to run off the rails, and also to prevent the car from entirely running off the rails in the event of any tendency of the flanges of the wheels to jump the rails.

45 A further object of the invention is to provide reinforcing rails serving the functions set forth, to reinforce the frame and act as guard rails, and which are further adapted to perform the function of sled runners, enabling the car to be easily and conveniently applied to or removed from the track without great effort on the part of the crew and in an expeditious manner, and

without causing damage to the running of the car.

55 The invention consists of the features of construction, combination and arrangement of parts, hereinafter fully described and claimed, reference being had to the accompanying drawings, in which:—

60 Figure 1 is a vertical transverse section, on the line 1—1 of Figure 2, through the frame and so much of a section car structure as is necessary to illustrate my invention.

Figure 2 is a bottom plan view of the 65 same.

Figure 3 is a sectional elevation taken on the line 3—3 of Figure 2.

Figure 4 is a similar section taken on the line 4—4 of Figure 1.

70 Figures 5 and 6 are side views of the guard and skid rails at opposite sides of the car.

Figure 7 is an enlarged detail transverse section on the line 7—7 of Figures 5 and 6.

75 Referring now more particularly to the drawings, a car frame is shown which, in general, may be one in common use. This frame includes top and bottom outer sills 1 and 2 and top and bottom inner sills 3 and 4 at one side of the frame, and a single sill 6 at the opposite side of the frame. Cross pieces 7 extend between these sills and form, with cross pieces 8 fastened to the sills 1, 2, 3 and 4, the frame structure proper 80 of the car. This frame structure carries a platform 9 of suitable type, suitable seats 10, a driving motor 11 and a fuel supply tank 12.

85 The pairs of sills 1—2, 3—4, are united 90 by bolts 13 and spacers 14, and the said sills carry bearings 15 for axles 16 on which are mounted flanged wheels 17, which are arranged for rotation between the said sills 1, 2, 3 and 4 at one side of the car frame. 95 At the opposite side of the car frame the cross bars 7 carry bearings 18 for the axles 19 on which the flanged wheels 20 at the opposite side of the car frame are mounted.

In practice, the motor 11 may be geared to 100 one of the shafts 16 for transmitting driving power thereto for the purpose of propelling the vehicle, and suitable connections between the motor 11 and fuel tank 12 are employed, as well as controlling devices for 105 governing the action of the motor. These

have not been shown as they are unimportant and constitute no part of my invention, and as means for this purpose of the kind in common use may be employed.

5 In accordance with my invention, I provide reinforcing, guard and skid rails 21 and 22 of similar form and construction, but of different lengths, at the opposite sides of the car frame. As shown, each of these 10 rails is of angle metal type, having a horizontal flange or web 23 and a depending vertical flange or web 24. Each rail is provided adjacent its ends with obliquely disposed offsets 25 terminating in end portions 26 lying above the plane of the body of the rail and parallel therewith. The rail 21 is disposed at one side of the car beneath the inner lower sill 4 and is secured at its ends thereto by bolts 27 passing through the horizontal web of the ends 26 and through the sills 3 and 4 and the intervening spacers 14. At intermediate points the rail 21 is also secured to the sill 4 by bolts 28 passing through the web 23, the said sill 4 and intermediate 15 spacers 29. The rail 22 at the opposite side of the car extends beneath the sill 6 and has its end portions 26 secured by bolts 30 to said sill and to the adjacent ends of the cross bars 7 or the bearings 18, while at intermediate points the rail 22 is secured to the sill 6 by bolts 31 passing through the web 23 of said rail, the sill 6 and intervening spacers 32. The construction and arrangement 20 of the angle metal rails 21 and 22 is thus such as to form braces beneath the sills which are firmly and rigidly tied thereto and which strengthen the framework to give it greater rigidity and freedom from excessive vibration, and which further serve to 25 resist lateral or tacking motions of the frame in the travel of the wheels over rough and uneven track rails, thus preventing to a large extent the tendency of the flanges of the wheels to ride over the track rails and throw 30 the car off the track.

It will also be observed that the bars 21 and 22 lie close to and in parallel relation with the flanges of the wheels 17 and 20, with their depending flanges 24 lying just 35 above the line of the heads of the track rails and the lower edges of the wheel flanges. By this arrangement the rails 21 and 22 are adapted to serve as guard rails to prevent 40 total displacement of the car from the track, in the event that one or more of the wheels should jump the track rails, the guard rails serving to abut against the track rails and to keep the car in alignment therewith and 45 prevent it from being thrown at an angle off the track, so that in case of partial displacement damage will be prevented or reduced to the minimum. The arrangement 50 of the reinforcing and guard rails is also such that their body portions will serve as supports or sled runners to adapt the car to

be easily and conveniently shifted onto or off the track. In shifting the car off the track it is simply necessary to turn the same until the wheels at the front or rear, that is, at one end of the car, are shifted off the rails, 55 whereby on turning the car the offsets 25 of the rails 21 and 22 at the opposite end of the car may be brought to rest on the balls of the track rails as guiding surfaces, allowing the car to be pushed until the lower 60 edges of the flanges 24 ride on the balls of the rails and serve as runners, so that the car may be easily slid off the track rails. In applying the car to the rails, one end of the car is turned to face the track rails and 65 the offsets 25 at such end brought into engagement as guiding surfaces with the track rails, whereupon the car may be slid into position upon the track through a sliding motion of the guard rails on the track rails. 70 With this construction, the car may be removed from the track with greater ease and convenience and less effort than a car of ordinary construction, and also in materially less time, this difference in time being of importance in preventing accidents. Another 75 advantage incident to the use of the rails 21 and 22 is that they prevent serious shocks and jars to and liability of breakage of the axles or wheel flanges, in shifting the car off 80 of or onto the track. They further serve as supports, when the car is removed from the track, to prevent the wheels from sinking down into soft soil, and for supporting 85 the car where no rest or set-off is available, so that it may be again easily shifted back 90 onto the track. Another material and important advantage of the invention is that 95 the rails 21 and 22 may be applied to sills of existing cars in use, with a gain of the 100 advantages stated, and with the further advantage of enabling frail car frames to be 105 strengthened so as to give better and longer service.

Having thus fully described my invention, I claim:

1. In a railway car, a frame having a sill at each side, flanged wheels lying outside the sills, and rails extending longitudinally beneath and terminally secured to the 110 sills and having body portions depending from the sills throughout the distance between the front and rear wheels, said body portions of the rails lying in a plane parallel with and close to and just above the 115 plane of the lower surfaces of the track engaging peripheries of the wheels.

2. In a railway car, a frame having a sill at each side, front and rear flanged wheels at each side, and angle metal rails 120 extending beneath the sills and terminally secured thereto, the rails having their body portions depending beneath the sills throughout the distance between the front and rear 125 wheels, said body portions of the rails ly- 130

ing in a plane parallel with and close to and just above the plane of the lower surfaces of the track engaging peripheries of the wheels.

3. In a railway car, a frame having a sill at each side, front and rear flanged wheels at each side lying outside the sill, and rails beneath the sills, each rail comprising a length of angle metal having a body portion, end portions and offset portions connecting said body portions with the end portions, the said portions of the rails being secured to the sills so as to dispose the body portions of the rails a distance below

15 the sills and to extend throughout the distance between front and rear wheels in a horizontal plane just above the plane of the lower portions of the peripheries of the wheels.

20 4. In a railway car, a frame having a sill at each side, sets of front and rear flanged wheels at the sides of the frame lying outside said sills, and combined guard and skid rails, one at each side of the frame,

25 secured to said sills, each rail having its body portion depressed relatively to its ends and extending the full distance between the wheels at its side of the frame, said body

30 portions of the rails lying in a horizontal plane adjacent to and just above the plane

of the lower surfaces of the track engaging peripheries of the wheels.

5. In a railway car, a frame having inner and outer pairs of superposed sills at one side and a single sill at its opposite side, 35 bearings carried by said pairs of inner and outer sills and arranged between the superposed sills at each pair, cross pieces connecting the pairs of sills at one side of the frame with the single sill at the other side 40 of the frame, bearings carried by said cross pieces above said single sill, front and rear flanged wheels at each side of the frame located outside of the sill and journaled in said bearings, and a combined guard and 45 skid rail at each side of the frame, one arranged beneath the single sill and the other beneath the lower sill of the inner pair of pairs of sills, said rails being secured to said sills and having body portions depressed below the plane of their ends, the body portions of the rails extending the full distance between the front and rear wheels and arranged in a horizontal plane close to but just above the horizontal plane of 55 the lower portions of the track engaging peripheries of the wheels.

In testimony whereof I affix my signature.

HAWKINS E. ROBESON.
